CLAIM

The ornamental design for a decorative container, as shown and described.

DESCRIPTION

FIG. 1 is a top isometric view of the decorative container; FIG. 2 is a top plan view of the decorative container as depicted in FIG. 1;

FIG. 3 is an elevational view of a first side of the decorative container as depicted in FIG. 1, the opposite side view being identical thereto;

FIG. 4 is an elevational view of a second side of the decorative container as depicted in FIG. 1, the opposite side view being identical thereto; and,

FIG. 5 is bottom elevational view of the decorative container as depicted in FIG. 1.

The features shown in dashed lines form no part of the claimed design.

1 Claim, 1 Drawing Sheet
